14 Claims.

(Cl. 68—267)

This invention relates to clothes wringers and more particularly to a wringer of improved design and construction having advantages in efficiency and safety not heretofore known in the art.

The primary object of this invention is to provide a pair of wringer pressure rolls with a conveyor whereby the work may be delivered between the rolls without the necessity of having the operator's hand come in close proximity to the pressure rolls themselves.

Another important object of this invention is to provide a relatively flat feed table for a wringer, such that the operator in feeding the wringer may place the work upon a plane surface of this feed table, rather than to be required to insert the work between the rolls as is necessary in conventional wringer constructions.

Another important object of the invention is to provide a wringer wherein the work is subjected to a primary and a secondary pressure application, the first pressure application being of such a relatively light nature that it cannot cause injury to the operator.

Another object of the invention is to provide a wringer wherein the pressure application may be maintained upon the work for a longer time interval than is afforded by the conventional wringer construction.

Other objects of the invention will appear hereinafter.

In the usual wringer construction which employs a pair of resilient rolls yieldably held in engagement with each other, there are two important disadvantages. The first of these is the fact that the operating pressure between the rolls must be very great in order to effectively extract the moisture from the work and that consequently this relatively great pressure is capable of causing serious injury to the operator in the event that her hands should come between the rolls. It is customary, of course, to provide wringers with emergency release controls, but it should be pointed out that these controls operate after the original injury has been done and that while it may prevent a more serious injury from occurring, they by no means eliminate the risks involved.

The second disadvantage in the conventional type of wringer is that the relatively narrow line contact afforded between the wringer rolls applies wringing pressure to the work only during a comparatively short time interval. Thus, in order to effectively extract the water from the clothes, it becomes necessary either that the

rolls be rotated quite slowly or that the operating pressure between the rolls be very great.

In the present construction these disadvantages have been overcome by providing a resilient feed belt which operates between the wringer rolls and around a pair of idler rolls in such a manner as to constitute a work conveyor having an almost horizontal table surface upon which the work may be placed by the operator without the necessity of requiring her to bring her hands into close proximity with the pressure rolls themselves. This feed belt then carries the work to and between the pressure rolls where the wringing action takes place and thereafter discharges the work from the wringer.

In order to still further increase the advantages and decrease the risks incident to the use of the wringer, two pressure rolls may be positioned side by side in a substantially horizontal plane, rather than one above the other as in the usual construction in order that the feed belt will be drawn around one of the rolls and partially encircle it before it passes between the contacting portions of the pressure rolls.

It will be readily understood that at this time the tension on the feed belt will cause this belt to engage the roll at the primary point of contact with a degree of pressure variable in accordance with the tension on the feed belt.

Referring now more particularly to the drawings in which I have shown the preferred embodiment of the invention:

Fig. 1 is a perspective view of the wringer assembly;

Fig. 2 is an end elevation of the wringer;

Fig. 3 is a longitudinal section through the wringer structure, being taken substantially on the plane of the line 3—3 of Fig. 6;

Fig. 4 is a transverse section through the wringer mechanism, being taken substantially on the plane of the line 4—4 of Fig. 3;

Fig. 5 is a transverse section taken on the line 5—5 of Fig. 3;

Fig. 6 is a detail plan section taken substantially on the plane of the line 6—6 of Fig. 5.

The frame structure of the present preferred embodiment of this invention as illustrated includes a pair of end housings 8 and 9, which are rigidly secured in spaced relationship with each other by means of a pair of tie-rods 11 and 12 which extend between the bosses 13 within the housing 8 and similar bosses 14 within the housing 9. It will be noted that each of these tie-rods 11 and 12 is provided with a reduced end portion in such a manner as to form a shoulder

15 which will abut against one of the bosses 13 or 14 and thus allow the housings 8 and 9 to be rigidly secured in position by means of the nuts 16 threaded on each end of each of the tie-rods 11 and 12. These tie-rods 11 and 12 are rigidly locked in position and are not free to rotate, but each is provided with one of the sleeves or idler rolls 18 and 19, rotatably mounted by means of the anti-friction bushings 17 secured within either end of each of the sleeves 18 and 19 and freely rotatable upon the tie-rods 11 and 12, respectively. The arrangement is such that the tie-rods act to maintain the housings 8 and 9 in their proper spaced relationship, while the sleeves 18 and 19 act as idler rollers, as will be more fully pointed out hereinafter.

An operating or roll-shifting rod 21 extends through openings 22 in the end walls of the housings 8 and 9 and is provided with operating control knobs 24 which may be secured to the rod 21 in any convenient manner, as, for example, by means of the cross pins 25. Preferably, these operating control knobs 24 are recessed within the depressions 27 formed in the housings 8 and 9, respectively, in order that they may be easily operated and yet be out of the way of the operator. The operating rod 21 includes threaded portions 31 and 32 and a pair of bearing arms 33 and 34 are secured thereto by means of the nuts 35 and lock washers 36. The bearing arms 33 and 34 extend angularly upwardly from the rod 21 and each is provided with a pair of flanges 37 and 38 between which bearing members 41 and 42 may be secured by means of the rivets 43. The bearing members 41 and 42 may be of any material customarily used for the purpose and are provided with openings in which the opposite ends of the shaft 44 of the shiftable roller 45 are journaled. The arrangement is such that the roll 45 and the bearing brackets 33 and 34 are rigidly held in their angular position with respect to the rod 21 and, therefore, manual rotation of either of the control knobs 23 and 24 will rotate the rod 21 in such a manner as to swing the roll 45 arcuately about the rod 21 as a center and thus enable the operator to shift the roll 45 from the position shown, downwardly through the dotted line position 45^a, illustrated in Fig. 3, and into the position 45^b, as shown by dotted lines in Fig. 4. The solid line position of the roll 45 and the dotted line position 45^b, as illustrated in Fig. 4, are the normal forward and reverse operating positions of this roll, while the position 45^a, illustrated in Fig. 3 is the fully released position as will hereinafter be explained.

A pair of latches 51 and 52 are pivotally mounted on the inner wall of the housing 9 by means of the cap screws 53 and 54, respectively. These latches are arranged in such a manner that the lower hook portion of the latch 52 will engage the flange 37 on the bearing arm 34 and serve to maintain this bearing arm 34 and the bearing 42 mounted therein in the position shown in Fig. 4, when the roll 45 is in its solid line or forward position, while the latch 51 will engage the flange 38 and maintain the parts in the dotted line position whenever the roll 45 is moved to the reverse position 45^a.

Manual release of the latches is accomplished by a release bar 55 mounted between the stud 56 journaled in the wall of the housing 8 and the stud 57 journaled in a boss 58 carried by the housing 9. This release bar 55 is rigidly secured to each of these studs 56 and 57 by the cross pins 59 and 61 in order that the operation of the re-

lease bar will be effective to rotate the head portions 62 and 63 of the studs 56 and 57. The lower half of these head portions 62 and 63 is notched as shown at 64 in order to form semi-circular releasing cams, as will be readily understood by reference to Fig. 4. Any manual movement imparted to the release bar 55 will be effective to rotate the head cam portion 63 of the stud 57 and force both of the latches 51 and 52 out of engaging position. When this occurs the latch 52 will disengage the flange 37 and the roll 45 will then be free to swing into the released position 45^a under the influence of gravity and under the tension of the feed belt 65. A coil spring 60 extends between the latches 51 and 52 in such a manner as to return them to the latching position and consequently to return the release bar 55 to its normal vertical position whenever no external forces are operating against the release bar. It will be understood that substantially identical latch members are housed within the housing 8, the latch member 66 therein corresponding to the latch 51 within the housing 9 while the latch 67 corresponds to and operates with the latch 52. These latches, of course, are adapted to engage the flanges 37 and 38 of the bearing arm 33 in order that the roll 45 may be rigidly maintained in proper operating position and that both of the bearings 41 and 42 may be properly secured against displacement.

A roll 75 is mounted in substantially horizontal relationship with the roll 45 and is adapted to cooperate therewith. The roll 75 includes a roll shaft 76, the end portions of which are journaled in the bearing members 77 secured between the flanges 78 and 79 of each of the bearing arms 80 and 81 by means of the rivets 82. Each of the bearing arms 80 and 81 extends downwardly and is pivoted upon the rod 21. In order to provide a freely rotatable connection between the rod 21 and the bearing arms 80 and 81, a pair of spacers 84 are placed over the threaded portions 31 and 32 of the rod 21 and each of these spacers 84 is clamped in position against one of the nuts 35 by means of one of the nuts 85. It will readily be seen from an examination of Fig. 3 that the spacer 84 is of greater thickness than the downwardly extending portion of the arm 81 and that for this reason the clamping action between the nuts 35 and 85 will act only upon the spacer 84 and will allow the bearing arms 80 and 81 to be freely rotatable upon the rod 21 without respect to the position of the control knobs 23 and 24.

It will be seen from Figs. 4 and 5 that with the rolls 45 and 75 in the position shown, the endless feed belt 65 will extend from the sleeve or idler roller 18 on the left hand side of the machine to the lower surface of the roll 75 and thence upwardly around the arcuate surface of the roll 75, between the pressure surfaces of the roll 75 and of the roll 45, and thence downwardly around the sleeve or idler roll 18 and horizontally back to the sleeve 18. When the parts are in this position, the portion of the feed belt 65 extending between the sleeve 18 and the roll 75 provides a flat feed table upon which the operator may place the work without the necessity of bringing her hands in close proximity to the rolls 45 and 75.

As the rolls are driven, the feed belt 65 will convey the work from the operator's hand to the roll 75 and thence upwardly between the roll 75 and the roll 45 in order to complete the wringing action. It should be particularly noted, however, that before the work reaches the point

of pressure existing between the roll 75 and the roll 45, it will be subjected to a relatively light pressure from the time that the belt 65 first engages the roll 75. Since in the embodiment of the invention here illustrated, the belt 65 encircles the roll 75 for about one-fourth of its circumference, it will be clear that the pressure here exerted by the belt is maintained for a much greater period of time than in the case of the pressure bearing between the two rolls. This factor increases the effectiveness as well as the safety of the wringer, since the bulk of the water contained by the work is removed before the work passes into the area of maximum pressure existing between the rolls 45 and 75. A more important advantage of this construction, however, arises from the fact that while the tension of the belt 65 is sufficient to apply a very noticeable degree of pressure to the work, yet it is not sufficient to injure the operator's hand in the event that it should inadvertently come between the belt 65 and the roll 75. In practice it has been found that if the operator's hand comes between the roll 75 and the belt 65, the pressure will be sufficient to cause momentary pain, with the result that the operator will involuntarily withdraw her hand and thus be in no immediate danger of more serious injury which might occur due to the relatively great operating pressure between the rolls 45 and 75.

In this connection it should be pointed out that in the conventional type of wringer, the operating pressure is necessarily so great that it will effectively prevent the operator from removing her hand unless some release mechanism is operated and that even though a release be effective almost instantaneously, the relatively great pressure will nevertheless cause a rather serious and painful injury. In the present construction, however, such undesirable results have been eliminated since the reduced pressure effective between the belt and the roll is not sufficient to either cause injury nor to prevent involuntary withdrawal of the operator's hand, but on the contrary is only sufficient to cause sufficient pain that the operator will automatically withdraw either as a result of a voluntary or of an involuntary reflex action.

A spring pressure unit 91 is provided at each end of the machine to properly maintain the resilient relationship between the roll 75 and the roll 45. Each of these spring units 91 includes a pilot rod 92 which is slidably mounted within internal bosses 93 and 94 formed within the housings 8 and 9, respectively. Each of the bosses so formed is drilled at 95 to receive the slideable pilot rod 92 and the outer ends of each of these drilled openings 95 are closed by means of plugs 96. A coil spring 97 is carried by each of the pilot rods 92 and is adapted to bear against the slideable collars 98 and 99, each of which is limited in its movement by the pins 101 and 102, which are adapted to move within the longitudinal slot 103 in the pilot rod 92. The spring yoke 104 is also slideably mounted upon the pilot rod 92 and is provided with a pressure pin 105 which extends through one of the openings 106 provided in each of the bearing arms 80 and 81. The arrangement is such that when the parts are in the position shown in Fig. 6, the 70 slideable sleeve 98 is limited in its movement by the pin 101 in such a manner that the compression spring 97 will bear against the collar 99 and thence against the adjusting bushing 107 in such a manner as to tend to slide the yoke 104 to the 75

right as shown in the drawings. Since the yoke 104 is operatively connected to the bearing 71 by means of the pressure pin 105, which engages the opening 106, the pressure exerted by the coil spring 97 will be effective to force the roll 75 into cooperating engagement with the roll 45.

As hereinbefore pointed out, roll 45 has two operating positions, the first being in the position shown and the second being in the dotted line position shown at 45^b. When the roll 45 has been moved to the position 45^b, it is, of course, necessary to reverse the action of the coil springs 97 in order that the proper pressure relationship between the rolls be established. To accomplish this a pair of pressure control levers 111 are provided, each of which is mounted upon a rotatable stud 112 journaled in a boss 113 within the wall of the housing 8 or 9, respectively. The enlarged inner head portions 114 of the studs 112 are each provided with an offset crank stud 115 in order to individually control the spring units 91. Each crank stud 115 carries a connecting rod 116 which extends through a drilled opening 117 near one end of the spring pilot 92 in such a manner that the operation of the offset crank pin 15 will move the spring pilot 92 longitudinally to the left in order that the roll 75 may be forced to the left as viewed in the drawings rather than to the right. Each boss 88 is provided with milled slots 118 in order to accommodate the connecting rod 116 which is preferably secured in position by means of a pair of cotter pins 119. When the pressure control arm 111 is rotated through 180° of movement the offset crank pin 115 will operate through the connecting rod 116 to slide the spring pilot 92 toward the left until the right hand end of the slot 103 engages the pin 102 and moves the collar 99 to the left against the pressure spring 97. As this occurs the collar 98 will come to bear against the adjusting bushing 108, thus tending to move the yoke 104, and pin 105 to the left, and thereby urge the roll 75 into pressure engagement with the roll 45^b. The continued leftward movement of the pilot 92 will, of course, compress the coil spring 97 in order that a proper initial tension may be maintained. The operating radius of the crank stud 115 has been so calculated as to provide a proper predetermined initial operating pressure and the adjusting bushings 107 and 108 threaded into the opposite ends of the yoke 104 may be adjusted by the operator from time to time in order to vary the operating pressure in accordance with the requirements of the work.

It should also be pointed out that each of the pressure control arms 111 are mounted on the outside of the housings 8 and 9, respectively, in such a manner that they are capable of movement somewhat greater than 180°, before engaging the stop portions 121 provided on the housings 8 and 9. This construction allows the offset crank stud 115 to move slightly beyond the dead center position at each end of its arc of movement in order that the force exerted by the springs 97 will hold the pressure control levers 111 in firm contact with the stop portions 121 and prevent any possibility of accidental release of the springs 97.

Driving means for the wringer is provided by extending the shaft 125 of the roll 45 through the bearing 41 and bearing arm 33 and providing it with a gear 126 which may be keyed or otherwise secured to the shaft 125. When the parts are in the solid line position shown, this

gear 126 will mesh with a somewhat similar gear 127 rotatably mounted upon a stud shaft 128 carried by the bracket 129 within the housing 8. The gear 127 is in turn driven by means of a gear 131, keyed to a shaft 132 having one end journaled in an anti-friction bushing 133 within a boss 134 in the wall of the housing 8, while the other end of the shaft 132 is similarly journaled in an anti-friction bushing 135 carried by a bracket 136 bolted to the inner wall of the housing 8 by means of a pair of cap screws 137. The shaft 132 is also provided with a bevel gear 141 which is similarly keyed in position and is adapted to mesh with and be driven by a similar bevel gear 142 keyed to a vertical drive shaft 143 journaled in anti-friction bushings 144 and 145 carried by the bracket 136 and by a boss portion 146, respectively. The boss 146 is preferably formed integrally with the housing 8 and may also serve as a mounting boss for the entire wringer structure in order that the wringer may be thereby pivotally mounted with respect to a washing machine and with respect to a wringer power transmission shaft adapted to transmit rotary driving force to the drive shaft 143 by means of the pin connection 147.

Means for reverse driving of the wringer have also been provided by this structure, since in order to drive the mechanism in the reverse direction when the roll 45 is moved to the position of 45^b, it is also necessary that the roll be shifted, for when this is done the gear 126 will disengage the gear 127 and engage the gear 131 which is, of course, revolving in an opposite direction to the direction of rotation of the gear 127.

In the operation of the machine, the work is placed on a flat feed table portion of the feed belt 65 and is thence carried to the roll 75 upwardly between the rolls 75 and 45 and thence downwardly toward the idler sleeve 19 at which point the work is discharged from the machine. In the normal operation the roll 45 will be secured against any movement by means of the latches 52 and 67 and any irregularities in the thickness of the materials being handled will be compensated for by yielding movement of the roll 75 as allowed by the spring units 91. When the operator desires to reverse the movement of the wringer she will operate the release bar 55 by pivoting it in either direction about the studs 56 and 57, thus causing the semi-circular cam portions of the enlarged inner heads 62 and 63 of these studs to act against the release latches 67 and 52 in order that they will disengage the bearing arms 33 and 34, respectively, and allow the roll 45 to drop into its released position 45^a. By manually rotating either or both of the control knobs 23 and 24 this roll may be moved upwardly to the position 45^b, at which time the flanges 38 of the bearing arms 33 and 34 will be engaged by the latch members 51 and 66 in order to maintain the roll in this position.

It should be pointed out that at this time the spring units 91 will be urging the roll 75 toward the right as viewed in the drawings and that for this reason no pressure will be exerted against the roll 45 as it is moved into the position 45^b. After the latches have engaged, the operating pressure between the rolls may be established by moving each of the pressure control levers 111 through somewhat more than 180° of movement in order to slide the spring pilots 92 longitudinally and cause the springs 97 to urge the

roll 75 to the left in order to engage the roll 45 in its new position 45^b.

While I have shown and described a preferred embodiment of this invention in accordance with the patent statutes, I am aware that it is subject to numerous modifications without departing from the invention spirit and I, therefore, do not wish to be limited except as by the scope of the appended claims.

I claim:

1. In a wringer, an idle pressure roll, a roll shaft therefor rotatably mounted in movable bearings, horizontally movable pressure springs associated with each of said bearings, spring guides for limiting the movement of said springs, manually operable control means for applying initial operating pressure to said springs at either end thereof and in either direction, a driven pressure roll, a roll shaft therefor mounted in movable bearings, means to guide the second roll into either of two limiting positions substantially in horizontal alignment with said idle pressure roll, manually operable roll shifting means associated with the guiding means to move said driven pressure roll from either of said operating positions to the other; means for rotatably driving said driven roll when in one of said operating positions, means for rotatably driving said driven roll in the opposite direction of rotation when in the other of said operating positions, releasable latches adapted to maintain said driven pressure roll in either of said limiting positions, a manually releasable control common to all of said releasable latches, an endless feed belt of elastic material extending substantially horizontally below said idle pressure roll and upwardly between said idle pressure roll and said driven pressure roll, and idler rollers supporting said feed belt.

2. In a wringer, an idle pressure roll, a roll shaft therefor rotatably mounted in movable bearings, movable pressure springs associated with each of said bearings, spring guides for limiting the movement of said springs, manually operable control means for applying initial operating pressure to said springs, a driven pressure roll, means to guide the second roll into either of two limiting positions, manually operable roll shifting means associated with the guiding means to move said driven pressure roll from either of said limiting positions to the other, means for rotatably driving said driven roll when in one of said operating positions, means for rotatably driving said driven roll in the opposite direction of rotation when in the other of said operating positions, releasable latches adapted to maintain said driven pressure roll in either of said operating positions, a manually releasable control common to all of said releasable latches, an endless feed belt extending between said idle pressure roll and said driven pressure roll, and idler rollers supporting said feed belt.

3. In a wringer, an idle pressure roll, a driven pressure roll, means to guide said driven pressure roll and bearings between an operating position on one side thereof, and an operating position on the opposite side of said idle pressure roll, roll shifting means adapted to move said driven pressure roll from either of said operating positions to the other, means for rotatably driving said driven roll when in one of said operating positions, means for rotatably driving said driven roll in the opposite direction of rotation when in the other of said operating positions, releasable latches adapted to maintain said driven

pressure roll in either of said operating positions, and a manually releasable control common to all of said releasable latches.

4. In a wringer, an idle pressure roll, a driven pressure roll, means for maintaining said driven pressure roll and bearings in an operating position, means for maintaining said driven pressure roll in an operating position on the opposite side of said idle pressure roll, roll shifting means adapted to move said driven pressure roll from either of said operating positions to the other, means rotatable in one direction, means rotatable in the opposite direction and means shiftable responsive to the roll shifting mechanism for engagement with one or the other of said rotatable means, to reverse the direction of rotation of the drive of said driven roll.

5. In a wringer, a plurality of idler rolls, an endless elastic feed belt extending around and carried by said idler rolls, a pair of pressure rolls intermediate said idler rolls and adapted to bear against and apply pressure to both surfaces of said feed belt, means for establishing operating pressure between said pressure rolls, manual release means for said rolls, means for shifting one of said pressure rolls with respect to the other pressure roll and with respect to the feed belt, means for rotatably driving said rolls, and means responsive to the operation of the said shifting means for reversing the direction of rotation of the rolls.

6. In a wringer mechanism including a frame, a pair of pressure rolls, and a coacting conveyor belt passing upwardly through the bite of the rolls, the combination of means for shifting one of said rolls and the belt between a forward operating position wherein the rolls and belt assume a characteristic wedge-like conveyor apron position on one side of a vertical plane in which the center of the machine structure lies and a reverse operating position wherein the rolls and belt assume a similar wedge-like conveyor apron position on the opposite side of said plane, said shifting means comprising means for moving one of said rolls in a path of movement whereby the axial spacing between said roll and its cooperating roll is increased to release the pressure effective between said rolls during the shifting movement; means responsive to said shifting movement for automatically reversing the direction of rotation of said rolls; pressure means whereby one of said pressure rolls may be spring urged in either of two directions to be forced into cooperating engagement with its cooperating roll in either the forward or reverse positions; said pressure means comprising an independent spring and reset lever at each end of said pressure rolls; and means whereby said pressure springs force said cooperating rolls out of engagement during the shifting movement of said rolls.

7. In a wringer mechanism including a frame, a pair of pressure rolls, and a coacting conveyor belt passing upwardly through the bite of the rolls, the combination of means for shifting one of said rolls and the belt between a forward operating position wherein the rolls and belt assume a characteristic wedge-like conveyor apron position on one side of a vertical plane in which the center of the machine structure lies and a reverse operating position wherein the rolls and belt assume a similar geometric position on the opposite side of said plane, said shifting means comprising means for moving one of said rolls in a

path of movement downwardly and below a relatively stationary cooperating roll; means responsive to said shifting movement for automatically reversing the direction of rotation of said rolls; and pressure means whereby one of said pressure rolls may be forced into cooperating engagement with its cooperating roll in either the forward or reverse positions.

8. In a wringer mechanism including a horizontal pair of coacting pressure rolls, one of said rolls maintaining a relatively fixed position and the other roll being shiftable to both sides of the fixed roll, and an endless clothes conveyor belt adapted to pass underneath the fixed roll and upwardly between the bite of the rolls and over the shiftable roll in such a manner as to provide a feed table portion in arcuate contact with the fixed pressure roll, a discharge conveyor portion and a return portion, the fixed pressure roll being positioned outside of the loop of the endless conveyor belt and the shiftable roll being shiftable within the loop of said conveyor belt, the shiftable positions constituting forward and reverse operating positions, a manually operable pressure release bar extending longitudinally of said first named pressure roll directly above said roll and outside of said belt loop, and a frame structure comprising a pair of end frames and longitudinal members wherein all of said longitudinal frame members are within said belt loop, the arrangement being such that all longitudinal parts of the wringer mechanism except the aforementioned fixed pressure roll and release bar are within the loop formed by the said endless conveyor belt.

9. In a wringer mechanism including a frame and a plurality of pressure rolls, the combination of spring means for applying operating pressure in either of two directions to one of the rolls, said spring means comprising a pair of springs, one spring of said pair being adapted to apply pressure at each end of said pressure roll, and a pair of pressure reset levers, each lever being adapted to apply pressure to one of said springs in either direction and independently of the other spring, each of said levers being capable of a movement of not less than 180° to afford great mechanical advantage against said springs.

10. In a wringer mechanism comprising a frame, pressure means comprising a plurality of pressure rolls, and spring means for maintaining said rolls in cooperating relationship, a substantially horizontal conveyor belt extending between idlers and adapted to pass below one of said rolls, between the rolls and above one of said rolls in order to provide a substantially horizontal feed table portion in tangential relationship with one of said rolls and a discharge conveyor portion in tangential relationship with the second roll, the straight run of said feed table portion between the points of tangency with said idler and pressure rolls being not less than the straight run of said discharge conveyor portion; and means for shifting said pressure roll means and said belt for reverse operation in such a manner as to provide a discharge conveyor portion of the belt on the side of the rolls formerly occupied by the feed table portion, and to provide a feed table portion having a straight run of not less than the straight run of said discharge conveyor portion, but positioned on the side of the wringer rolls formerly occupied by the discharge conveyor portion.

11. In a wringer mechanism including a frame, roll supporting means, and roll driving means,

the combination of an endless feed belt, a central spring-urged pressure roll positioned above the top surface of the belt to provide a feed table portion of said belt on one side of the roll, and a discharge conveyor portion on the other side of said roll, a cooperating pressure roll adapted to be shifted between a forward and a reverse operating position, one on either side of said central roll and so positioned as to reverse the positions of the feed table portion and discharge conveyor portion of said belt; means for applying pressure to said first named central pressure roll to urge said roll in either direction whereby it may be forced into cooperating relationship with said second roll in either of the above named positions; means for driving said rolls and belt in a forward direction while the second roll is in one of its two positions; and means responsive to the shifting of the second roll to said reverse position for driving the mechanism in a reverse direction.

12. In a wringer mechanism including a frame, roll supporting means, and roll driving means, the combination of a resilient endless feed belt operating between a pair of idler rollers to provide a feed table portion and a discharge conveyor portion on the upper run of said belt and a return portion on the lower run of said belt, a central spring urged pressure roll above the top surface of said conveyor portion of said belt and positioned at approximately the mid point of the length of the belt loop, a cooperating pressure roll adapted to be shifted between two operating positions, one on either side of said spring urged roll in such a manner as to reverse the positions of the feed table portion and discharge conveyor portion of said belt, and means for applying spring pressure to said first named central pressure roll to urge said roll in either direction whereby it may be forced into cooperating relationship with said second roll in either of the above named positions.

13. In a wringer mechanism including a frame, roll supporting means, and roll driving means, the combination of a resilient endless feed belt operating between a pair of idler rollers to provide a feed table portion and a discharge conveyor portion on the upper run of said belt and a return portion on the lower run of said belt,

a central spring urged pressure roll above the top surface of said conveyor portion of said belt and positioned at approximately the mid point of the length of the belt loop, a cooperating pressure roll adapted to be shifted between two operating positions, one on either side of said spring urged roll in such a manner as to reverse the positions of the feed table portion and discharge conveyor portion of said belt, means for latching said cooperating pressure roll in either of said two positions, means for applying spring pressure to said first named central pressure roll to urge said roll in either direction whereby it may be forced into cooperating relationship with said second roll in either of the above named positions, means for driving the mechanism in forward direction while the second roll is in one of its positions with respect to the first roll, means responsive to the movement of the second roll to its other position for driving the mechanism in a reverse direction, and a single manually operable release bar adapted to disengage the said latching means responsive to manual movement in either of two possible directions of movement.

14. In a wringer, a relatively fixed pressure roll, a roll shaft therefor rotatably mounted in movable bearings, movable pressure springs associated with each of said bearings, spring guides for limiting the movement of said springs, manually operable control means for applying initial operating pressure to said springs, a co-acting shiftable pressure roll, means to guide the shiftable roll into either of two limiting positions substantially in horizontal alignment with said fixed pressure roll, roll shifting means associated with the guiding means to move said shiftable roll from either of said limiting positions to the other, means for rotatably driving said shiftable roll when in one of said operating positions, means for rotatably driving said shiftable roll in the opposite direction of rotation when in the other of said operating positions, release latches adapted to maintain said shiftable roll in either of said operating positions, and a feed belt running below said fixed pressure roll and upwardly between said fixed roll and said shiftable roll.

NICHOLAS L. ETSEN.
